BACK GAUGE FOR PUNCHES

George H. Dawson, Chicago, Ill., assignor to
Wilson-Jones Company, Chicago, Ill., a corpora-
tion of Massachusetts

Application September 19, 1934, Serial No. 744,629

6 Claims. (Cl. 164—91)

This invention relates to a gauge for punches by means of which the distance between the punching and the back edge of the punched sheets may be regulated.

5 It is an object of this invention to provide a simple and efficient gauge that may be easily and accurately adjusted, without the use of any tools, to regulate the distance a sheet of material to be punched may be inserted into the mouth 10 of the punch. It is a further object of this invention to provide a gauge that will stay in any position to retain the exact adjustment desired. It is a further object of this invention to provide a gauge mounted on the base of the punch, rather 15 than on the punch head, so that only two gauges will be required for any punch, regardless of the number of punch heads on the punch. Other objects of this invention will become apparent upon reading the following description taken in conjunction with the accompanying drawings, in which

Figure 1 is a perspective view of a punch embodying the invention;

Figure 2 is a fragmentary top plan view of one end of the punch shown in Figure 1;

Figure 3 is a cross sectional view taken on the line III—III of Figure 2, looking in the direction of the arrows, with parts broken away to facilitate illustration of the structure;

Figure 4 is a cross sectional view through a different type of punch showing a modified form of back gauge;

Figure 5 is a view similar to Figure 4 showing another modified form of back gauge;

Figure 6 is a cross sectional view of the punch of Figures 1 to 3, showing a modified form of back gauge; and

Figure 7 is a view similar to Figure 6 showing another modified form of back gauge.

40 In the drawings, the reference numeral 2 indicates a base member provided with a removable chip pan 3. The chip pan is provided with a covering 4 of felt or similar material to provide an attractive appearance and to protect the finish on any surface on which the punch might be handled. The side walls 5 of the base extend at a slight angle from the vertical, as shown in Figure 3, and the edges 6 of the chip pan are bent so as to provide a resilient engagement between the chip pan and the base.

50 The base member 2 is provided at each end with an integral upstanding ear 8. A hollow rod 9 is supported in apertures positioned adjacent the rear of the ears 8. A wire 10 of any desired configuration may be positioned within the hollow rod 9. The end 11 of the wire 10 is bent to form a side gauge for the punch. The wire 10 is secured within the rod in any desired position by means of a thumb screw 12.

60 The rod 9 also helps support a plurality of

punch heads 13. The top surface 14 of the base is provided with a ledge 15, Figure 3, to support the front end 16 of each punch head. Another ledge 17, positioned at the rear of the base member 2, has its forward edge terminating adjacent the rear of the punch heads to provide an open space through which the punchings may reach the chip pan. A plate 18 is secured to the base 2 adjacent the flange 15 to cover the front ends 16 of the punch heads. The plate 18 may carry a scale 19 and any suitable identification means 20. The punch heads 13 are slidable along the rod 9 and may be secured in any desired position by means of thumb screws 21. The punch heads may be marked, as indicated at 22, to facilitate proper positioning with respect to the scale 19.

Each punch head is provided with a punching pin 23 having its cutting edge of any desired shape. The pin 23 fits in a recess 24 having a portion 25 of reduced cross sectional area. The lower portion 26 of the punching pin is reduced in cross sectional area to fit the restricted passage 25. A coiled spring 27 encircling the reduced portion 26 of each punching pin bears against the larger portion of the pin and against the shoulder 28 to exert a constant force tending to raise the punching pin.

A horizontal slot 29 passes through the restricted passage 25 of each punch head to form a mouth or jaw into which the sheets to be punched are inserted. The distance the sheets travel into the mouth determines the spacing of the apertures punched from the edge of the paper. A pair of back gauges 30, spaced a suitable distance apart, regulate the distance the sheets to be punched may be inserted into the mouth of the punch heads.

The back gauge 30 includes a flat strip of metal bent to form a horizontal portion 31 lying against the upper surface of the flange 17, a curved portion 32, a second horizontal portion 33 having a semi-circular depression 34 fitting around the lower half of the hollow rod 9, and a vertical portion 35 having its lower end positioned adjacent the front surface of the flange 17. A flat metal plate 36 is welded to the vertical portion 35 to increase the effective thickness of the vertical portion of the back gauge. The resiliency of the metal serves to hold the back gauge between the ledge 17 and the rod 9 in any desired lateral position against accidental movement. However, the back gauge may be moved laterally by the application of a moderate lateral force.

The portions 32 and 35, 36 are provided with registering threaded apertures to permit a screw 37 to extend therethrough. The screw 37 is provided at one end with a knurled head 38 and at the other end with a flat disk 39 permanently secured thereto in any suitable manner. The disk 60

39 is in the same horizontal plane as the mouth 29 of the punch heads. Rotation of the screw 37 moves the disk 39 forward or backward to regulate the distance sheets may be inserted into the mouth of the punch heads.

The metal plate 36 may be welded to either side of the vertical portion 35. The end of the screw 37 projecting beyond the curved portion 32 is preferably provided with a lock nut 36'. 10 However, the lock nut may be omitted if the portion 35 has sufficient thickness, because the resiliency of the metal of which the back gauge is formed will generally be sufficient to retain the screw 37 against accidental rotation.

15 The punching pins 23 are operated simultaneously by pressure on a single lever 40 secured to one end of an operating shaft 41 which passes through each punch head 13 and the two, up-standing ears 8. The lever 40 retains one end 20 of the shaft 41 in position. The other end of the shaft 41 is secured by means of a latch 42 pivoted to the adjacent ear 8 by means of a screw 43. The shaft 41 is provided with a longitudinal notch 44 adapted to engage a projection 45 on 25 each punch head to force the punching pin through the passage 25 across the slot 29 to perforate any sheets positioned in the jaw of the punch. The lower end of the passage 25 is preferably slightly enlarged, as indicated at 25', 30 Figure 3, to enable the punchings to fall through into the chip pan. When the lever 40 is released after the punching operation, the spring 27 forces the punching pins upwardly into position for the next punching operation.

35 In Figure 4 I have illustrated a modified form of back gauge particularly suited for large punches, where the distance from the back of the punch to the inner end of the sheet receiving jaw is considerably greater than in the punch illustrated in Figures 1 to 3. Referring to Figure 4, a punch base 46 has two bars 47 and 48 extending across one edge of the punch. These bars help to support a plurality of punch heads 49. A plate 50 covers the front end of the punch 45 heads. A suitable scale is preferably provided on the surface of the plate 50 adjacent the end of the punch heads. The operation of the punching structure is the same as that of Figures 1 to 3. Accordingly, it is believed to be unnecessary to describe the punching mechanism in detail.

50 The back gauge comprises a flat strip of metal bent to provide a pair of spaced vertically extending portions 51 and 52. The end of the portion 51 is bent into a horizontal plane, and rests 55 on the bar 48, as indicated at 53. The horizontal portion 54 connecting the upper ends of the portions 51 and 52 has a semi-circular depression 55 to receive a rod 56 similar to the rod 9. The portion 52 is reinforced by an L-shaped plate 57 60 having its short leg 58 welded to the surface of the portion 52. The plate 57 is preferably of greater thickness than the strip 51—55 to provide sufficient thickness for a threaded aperture through the portions 52 and 58 which are welded together.

65 A screw 59, similar to the screw 37, is threaded through the threaded aperture through the portions 52 and 58. The screw also passes through an aperture provided in the portion 51. Although 70 the resiliency of the metal will generally hold the screw 59 in any desired position, I prefer to

eliminate any possibility of accidental movement of the screw by providing a lock nut 60 between the head of the screw and the portion 51 of the back gauge.

In Figure 5 the back gauge comprises a single 5 flat strip of metal 61 having one end resting on the bar 47 and its other end bent to form a vertical portion 62 and a horizontal portion 63 fitting under the rod 56. An angular metal piece 64, of suitable thickness, has one leg welded to the strip 61 and the other extending upwardly to receive the screw 59.

Figures 6 and 7 illustrate modified forms of back gauges suitable for use with the punch illustrated in Figures 1 to 3. In these modifications the only difference is in the specific means for supporting the screw 37. In Figure 6 a flat strip has one vertical leg 65 resting on the ledge 17 and another vertical leg 66 resting on the chip pan 3. A horizontal portion 67, similar to the portion 33, connects the upper ends of the legs 65 and 66. The front surface of the leg 66 is reinforced by a relatively thick metal plate 68 welded thereto.

In the modified form illustrated in Figure 7, 25 a casting 69, of any suitable shape, is substituted for the bent metal structure of the other embodiments.

Although I have described several embodiments of my invention in detail, it will be understood 30 that the description thereof is illustrative, rather than restrictive, as many details may be modified or changed without departing from the spirit or scope of my invention. Accordingly, I do not desire to be limited to the exact construction described, except as limited by the appended claims.

I claim:

1. In a punch, a bent strip of metal resiliently held against a lateral movement, a screw threaded through portions of said strip, and a flat disk 40 secured to one end of said screw.
2. In a punch, a punch head provided with a jaw adapted to receive sheets to be punched, a resilient strip of metal secured to said punch independently of said punch head, a screw threaded through said strip, and an enlargement on one end of said screw adapted to limit the distance sheets may be inserted into said jaw.
3. In a punch, a punch head provided with a jaw adapted to receive sheets to be punched, a 50 rod extending the length of said punch, and a back gauge supported between said rod and the base of said punch independently of said punch head.
4. In a punch, a base member, a pair of up-standing ears on said base, a rod supported by said ears, and a resilient back gauge supported by said base and said rod.
5. In a punch, a base member, a rod extending longitudinally of said base and spaced thereabove, and a resilient back gauge slidably supported between said rod and said base.
6. In a punch, a base member, a pair of spaced supports extending longitudinally of said base member, a rod spaced above one of said supports, 65 and a back gauge having one end supported between said one support and said rod, the other end of said back gauge being supported on said other support.

GEORGE H. DAWSON. 70
